(57) **CLAIM**

The ornamental design for a phone case, as shown and described.

DESCRIPTION

FIG. 1 is a top, front and right side perspective view of a phone case, showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a bottom, rear, and left-side perspective view thereof showing the support stand portion of the phone case in an open state.

The broken lines shown in the drawings depict the portions of the phone case that form no part of the claimed design.

1 Claim, 9 Drawing Sheets
